DESIGN

CATHERINE O'HARA

A LADY'S DRESS.

15,130

Patented July 8, 1884

UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S DRESS.

SPECIFICATION forming part of Design No. 15,130, dated July 8, 1884.

Application filed May 23, 1884. Term of patent 3½ years.

To all whom it may concern:

Be it known that I, CATHERINE O'HARA, of the city, county, and State of New York, have invented and produced a new and original Design for a Pattern of a Lady's House Dress, (numbered 9,257;) and I do hereby declare that the engraved prints accompanying this specification convey to any one accustomed to using paper patterns a clear understanding 10 of how a garment made up by the pattern will appear.

The design shows a round walking-skirt and a basque. The skirt displays two deep flounces all around; the basque exhibits deep, closely-

fitted fronts that describe a point below the closing and an arched effect at the sides; a short, closely-fitted back; a deep flounce depending from the lower edge; a standing collar, and coat-sleeves.

What I claim as my invention, and desire to secure by Letters Patent, is—

The design for a lady's house dress, as shown in the engraved prints accompanying this specification.

CATHERINE O'HARA.
